Primary Examiner — Mary Shannon Malley*Assistant Examiner* — Olivia H Aldin(74) *Attorney, Agent, or Firm* — NIXON & VANDERHYE P.C.**CLAIM**

The ornamental design for a clip as shown and described.

DESCRIPTION

FIG. 1 is a front perspective view of a clip;

FIG. 2 is a front view thereof;

FIG. 3 is a rear view thereof;

FIG. 4 is a top view thereof;

FIG. 5 is a bottom view thereof;

FIG. 6 is a right side view thereof;

FIG. 7 is a left side view thereof;

FIG. 8 is a rear perspective view thereof; and

FIG. 9 shows the clip in an environment of use; and,

FIG. 10 shows the clip in another environment of use.

The dash-dash broken lines in FIGS. 9 and 10 depicting a human figure and a second clip illustrate environmental subject matter that forms no part of the claimed design. The remaining dash-dash broken lines depict portions of the clip that form no part of the claimed design. The dotted line in FIGS. 3, 4, 6-8 depict the boundaries of the claimed design and forms no part thereof.

1 Claim, 6 Drawing Sheets(56)
